UNITED STATES PATENT OFFICE

MARTIN J. KERMER, OF SNYDER, NEW YORK, ASSIGNOR TO BUFFALO FOUNDRY & MACHINE COMPANY, OF BUFFALO, NEW YORK, A CORPORATION OF NEW YORK

CONCENTRATOR

Application filed August 20, 1930. Serial No. 476,533.

This invention relates to a concentrator which is more particularly intended for evaporating or boiling solid containing liquor to a high density such as caustic soda, calcium chloride, etc. Such liquors are usually concentrated from 50% to 85% and to accomplish this within a reasonable time the material is subject to comparatively high pressure while being concentrated.

The apparatus heretofore proposed for this purpose was of such construction that it was very difficult and expensive to produce a tight fit between the several parts forming the inlet and outlet manifolds for the heating medium and also required the removal of an undue number of parts when access was necessary to the apparatus for cleaning, inspection and repairing of the heating tubes, and the construction was also such that only a comparatively low pressure could be used which rendered it impossible to effect concentration of the liquor to the desired high density.

It is the object of this invention to provide a concentrator for this purpose which is comparatively simple in construction, which is so constructed that high pressure can be used, which can be easily maintained tight between the inlet and outlet manifolds of the heating medium without requiring very accurate and expensive workmanship, and which permits of inspecting, repairing and adjusting the heating tubes upon removal of comparatively few parts.

In the accompanying drawings:

Fig. 1 is a vertical section of a concentrator embodying a satisfactory form of my invention.

Figs. 2 and 3 are horizontal sections taken on the correspondingly numbered lines of Fig. 1 and looking in the direction of the arrows associated with these lines.

Fig. 4 is a fragmentary vertical section, on an enlarged scale, of one of the improved tube units showing the manner of mounting the same in accordance with this invention.

Fig. 5 is a similar view showing the manner of mounting a tube unit in common use heretofore.

Fig. 6 is a horizontal section taken on line 6-6, Fig. 4.

In the following description, similar characters of reference indicate like parts in the several figures of the drawings.

In its general organization the concentrator comprises a concentrating chamber adapted to contain the liquor to be concentrated, a plurality of plain heating tube units arranged in the concentrating chamber and each having an inlet for the heating medium and an outlet for the condensate of said heating medium, a plurality of special heating tube units arranged in the concentrating chamber and each having an inlet for the heating medium and an outlet for the condensate of said heating medium, an inlet manifold or chamber adapted to distribute the heating medium to the inlets of the several tube units, and an outlet manifold or chamber adapted to receive the condensate from the outlet of the several tube units and discharge the same from the apparatus.

The concentrating chamber 10 may be variously constructed but as shown in the drawings, the same comprises an upright cylindrical side wall 11 of sheet metal, a sheet metal dome 12 connected with the upper end of the side wall and having a central outlet 13 for the vapor of the liquor which is being boiled, said outlet leading to the atmosphere or to a condenser or exhausting device of any suitable character if it is desired to form a partial vacuum in said concentrating chamber, and a bottom preferably of cast iron and consisting of an upper marginal horizontal tube sheet or ring 14 provided at its outer edge with an annular upstanding flange 9 secured to the lower edge of the side wall 11 and provided at its inner edge with a downwardly tapering discharge spout 15 which has an outlet 16 at its lower end for the finished material which outlet may be controlled by a valve or closure of any approved construction. The liquor to be concentrated may be supplied to the concentrating chamber in any suitable manner for example by a supply pipe 17 connecting with the lower end of the concentrating chamber, as shown in Fig. 1.

On its exterior the spout 15 is provided at

a distance from its upper end with an upper annular flange 18 and further down on the exterior of said spout the same is provided with a lower annular flange 19.

Arranged below the marginal ring of the bottom of the concentrating chamber and spaced outwardly from the discharge spout 15 is an annular manifold wall which is connected by screws 20 or otherwise with the underside of the bottom ring 14 and consists of an upper wall section 21 of comparatively small diameter and a lower wall section 22 of relatively larger diameter, thereby forming an internal annular downwardly facing shoulder 23 on this wall between its upper and lower sections. This shoulder is horizontally in line with the underside of the upper flange 18 of the discharge spout 15 and the lower edge of this wall is horizontally in line with the underside of the lower flange 19 of said spout, as shown in Fig. 1.

Between the central part of the manifold wall and the discharge spout is arranged an intermediate partition ring or lower tube sheet 24 which latter is secured at its inner edge to the underside of the spout flange 18 by screws 25 and also secured at its outer edge to the underside of the shoulder 23 of the manifold wall by screws 26, thereby forming, with the wall section 21, the upper part of the spout 15 and the bottom ring 14 of the concentrating chamber, an annular outlet manifold chamber 27 into which the outlets of the heating tube units open for receiving the condensate therefrom and from which this condensate is discharged by a pipe 28 connected with the upper section of the manifold wall.

Surrounding the intermediate part of the discharge spout is a lower closure ring or annular cover 29 which is secured at its inner edge to the underside of the flange 19 by screws 30 and also secured at its outer edge to the lower edge of the manifold wall by screws 31, thereby forming, with the adjacent part of the spout, the lower tube sheet or ring 24 and the lower section 22 of the manifold wall; an annular inlet manifold chamber 32 which distributes the steam to the inlets of the several heating tube units. This steam for heating is supplied to this inlet manifold by a pipe 33 connected with the lower section 22 of the manifold wall, or by any other suitable means.

Within the lower part of the concentrating chamber is arranged a downtake tube 34 which is spaced from the side wall of this chamber by an annular uptake passage 35, said downtake tube communicating at its upper end with the upper part of the concentrating chamber and also communicating at its lower end with the annular uptake passage by a lateral passage 36 which is formed by terminating the lower end of the downtake tube at a distance above the bottom ring

14 and supporting this tube on brackets 37 arranged on the upper side of said ring, as shown in Fig. 1.

The heating tube units are arranged in a plurality of rows within the uptake passage 70 between the wall of the concentrating chamber and the downtake tube, the greater number of these units being of the plain type and mounted in the usual and well known manner but a sufficient number of the specially 75 mounted type are interspersed with the plain type for the purpose of attaining the objects of this invention.

Each of the plain heating tube units includes an upright inner inlet tube 38 which has its lower end secured in an opening 39 in the lower tube sheet 24 and communicating with the inlet manifold chamber 32 while its intermediate part passes loosely through a condensate outlet opening 40 in the upper tube sheet 14 and terminates at its upper end adjacent to the upper end of the downtake tube 34. The upper part of the outlet opening 40 is counterbored and in the same is secured an externally screw threaded coupling 41 which projects above the upper tube sheet and has its bore of larger diameter than the external diameter of the respective inlet tube 38 so as to leave an outlet passage 42 between them for the escape of the water of condensation when using steam as the heating agent in the concentrator. Surrounding the upper part of the inlet tube 38 within the concentrating chamber is an outer tube 43 of larger diameter so as to leave an 100 annular space 44 therebetween which outer tube has a closed top 45 and connected at its lower end by a screw joint with the upper end of the coupling nipple and also bears at its lower end against a packing 46 on the upper tube sheet so as to form a tight joint therewith, as shown in Fig. 5. The steam passes from the inlet manifold upwardly through the inner tube 38 of each plain heating tube unit, thence downwardly through the space between the inner and outer tubes 38, 43, so as to heat the liquor in the concentrating chamber, thence through the passage 42 in the nipple 41 and the opening 40 in the upper tube sheet and thence into the outlet manifold 27 and out through the discharge pipe 28 thereof.

Each of the special heating tube units is constructed and mounted as follows, and as best shown in Figs. 4 and 6: The numeral 126 47 represents an upright inner inlet tube which has its lower part passing through the lower tube sheet 24 and its intermediate part passing through the upper tube sheet and terminating at its upper end adjacent to the 125 upper edge of the downtake tube 34. Surrounding the lower part of the inlet tube is a draft tube 48 of larger diameter than the inner tube 47 so as to leave an annular drain passage 49 therebetween said draft tube also 130

passing with its lower part through the lower tube sheet 24 and extending with its upper part into the upper tube sheet 14. The lower end of the draft tube is screwed into a tubular screw nut 50 which bears against the underside of the tube sheet 24 and the lower end of the inlet tube 47 is also screwed into this tubular nut 50 and communicates with the inlet manifold chamber 32.

10 The upper end of the draft tube 48 is arranged within an opening 51 in the upper tube sheet 14 and is provided with an enlargement or head 52 forming a downwardly facing shoulder 53 on the draft tube which 70 engages with an upwardly facing shoulder 54 formed in the opening 51 by counterboring the upper part of the latter, as shown in Fig. 4. The upper and lower tube sheets 14, 24 are braced relative to each other and 75 held in a definite spaced position by spacing sleeves 55 each of which surrounds one of the draft tubes 48 but is preferably of somewhat larger diameter so as to leave an annular space 56 therebetween, and each of 80 these spacing sleeves engaging its lower end with a countersunk seat 57 on the upper side of the lower tube sheet and engaging its upper end with a countersunk seat 58 on the underside of the upper tube sheet, as shown in Fig. 4. Upon tightening the screw nut 50 the draft tube 48 acts like a screw bolt and causes the upper and lower tube sheets 85 to be firmly drawn against the opposite ends of the spacing sleeve, thereby producing a 90 very strong construction which is capable of withstanding high steam pressures and thus enabling a higher density in the liquor to be obtained than would otherwise be possible. The draft tube 48 and the spacing 95 sleeve 55 are provided, respectively, adjacent to the upper side of the lower tube sheet 24 with drain openings 59, 60 to permit the condensate of the steam to escape therefrom into the outlet manifold chamber as will presently appear.

100 The numeral 61 represents an externally screw threaded coupling nipple which is secured with its lower end in the enlarged upper part of the tube opening 51 in the upper tube sheet and a bore of larger diameter than the exterior of the respective inlet tube 47 so as to leave a passage 62 between the same. Surrounding the upper part of the inner tube is an outer or outlet tube 63 of larger 105 diameter forming a down passage 64 between the same, which outer tube has a closed top 65 and has its lower end connected by a screw joint with the upper end of the respective nipple 61 and engaging with a packing 66 on the upper side of the upper tube sheets as to form a tight joint between the same. The steam entering the inlet manifold 110 32 passes from the latter upwardly through the inner tube 48, thence downwardly through the outer tube 63 and heats the

liquor in contact with the latter, then passes successively through the nipple 61, the draft tube 48 and its opening 59, the spacing sleeve 55 and its opening 60, and the outlet manifold chamber 27 to the discharge pipe 28.

70 Due to this construction a much higher steam pressure can be used in the apparatus, a more rapid concentration is effected and the liquor can be concentrated to a higher density, this being due to the means of mounting the special tubes which imparts added strength to the tube sheets and holds the same reliably in place so as to maintain leak-tight joints between the heating tubes and the tube sheets and the parts associated therewith.

75 Moreover, by constructing the manifold chambers in the manner shown and described the tubes are easy of access when required, the same are capable of withstanding high pressure without becoming distorted and leaking at the joints and it is possible to machine the parts and assemble the same so as to produce a good fit without incurring undue expense or requiring a high degree of accuracy which usually involves high cost.

80 When it is desired to gain access to the lower ends of the tube units this is possible upon removing the cover 29 and also the lower tube sheet 24 without disturbing the manifold wall, thereby enabling this operation to be performed with ease and facility when required.

85 I claim as my invention:

1. A liquor concentrator comprising a concentrating chamber having at its lower end an annular upper tube sheet and a downwardly projecting spout arranged on the central part of said upper tube sheet and provided externally with upper and lower flanges, a manifold wall surrounding said spout and connected at its upper edge with said upper tube sheet and provided internally with a downwardly facing shoulder which is arranged in line with said upper flange and having its lower end arranged in line with said lower flange, an annular lower tube sheet having its inner edge secured to the underside of said upper flange and its outer edge secured to the underside of said shoulder and forming with said spout, wall and upper tube sheet an upper manifold chamber, an annular cover secured at its inner edge to the underside of said lower flange and at its outer edge to the lower edge of said wall and forming with said spout, wall and lower tube sheet a lower manifold chamber, and heating tube units each having an inlet communicating with one of said chambers and an outlet communicating with the other chamber, the opening closed by said cover being larger than the opening closed by said lower tube sheet so that the latter can be removed through said opening which is closed by said cover.

120 2. A liquor concentrator comprising a con-

centrating chamber having at its lower end an upper tube sheet, an upper manifold chamber arranged below said upper tube sheet and having a lower tube sheet, a lower manifold chamber arranged below the upper manifold chamber and having at its lower end a cover, a heating tube unit including an inner tube having its lower part extending through said lower tube sheet and an outer tube arranged within the concentrating chamber and surrounding the upper part of said inner tube, a screw nipple surrounding said inner tube and connecting the outer tube with said upper tube sheet, a draft bolt having a tubular body surrounding said inner tube, an upper head bearing downwardly against said upper tube sheet and a lower tubular nut bearing upwardly against said lower tube sheet, said tubular nut also supporting the inner tube at its lower end, and a tubular spacer surrounding the tubular bolt and said tubular spacer engaging its upper and lower ends with said upper and lower tube sheets, respectively, said inner tube communicating with said lower manifold chamber, and said tubular bolt and spacer having side openings for placing the nipple and outer tube in communication with said upper manifold chamber.

30 In testimony whereof I hereby affix my signature.

MARTIN J. KERMER.
